UNITED STATES PATENT OFFICE.

ANTHONY H. G. FOKKER, OF AMSTERDAM, NETHERLANDS, ASSIGNOR TO ATLANTIC AIRCRAFT CORPORATION, A CORPORATION OF NEW JERSEY.

LATERAL CONTROL FOR AIRPLANES.

Application filed August 26, 1922, Serial No. 584,595, and in Germany March 22, 1921.

The present invention relates generally to improvements in airplanes and is more especially directed to a method and means of effecting lateral control thereof in flight.

It is well known that the actuation of the ailerons, by means of which the air flow is modified and the camber of the wings and the angle of incidence altered to give greater or less lift in maintaining lateral balance in the usual type of airplane, causes the airplane to deviate from its straight line of flight. This follows from the differential of resistance which is set up when one aileron is lowered and the other raised, the increased resistance against the lowered aileron tending to produce a turning movement of the airplane from its line of flight. To correct or overcome this tendency of the present types of airplanes to change their direction of flight on the actuation of the ailerons, it is necessary to simultaneously operate the rudder to the right or left as the case may be. Obviously, the necessity of functioning the directional control or rudder in conjunction with the lateral control, if a straight line of flight is to be maintained by the airplane, is a serious defect in airplane construction as at present constituted. This is especially true, when the airplanes are being operated by novices or inexperienced aviators.

The general object of the present invention is to provide a simple method and means to obviate the necessity of operating the rudder or directional control of the airplane, when the ailerons or flaps are actuated, in order that a straight line of flight may be maintained, thus enabling the aviator to operate the airplane with a minimum of effort with a consequent increase in the factor of safety.

More specifically, it is the object of my invention to provide a method of effecting the practical equalization of the resistance of the ailerons when normally actuated, the elimination of the differential in the resistance of the ailerons overcoming the tendency of the airplane to turn from its straight line of flight, thereby rendering the operation of the rudder or directional control in conjunction with the lateral control unnecessary.

A further object of my invention is to provide a means of practicing my invention, which is subject to general application in

airplane construction, thus permitting its incorporation in existing structures at a minimum of cost.

Other objects and advantages of my invention will become manifest as the description proceeds, and I would have it understood that I reserve unto myself all rights to the full range of equivalents, both in structure and uses, to which I may be entitled.

For the purposes of the present disclosure, I have elected to illustrate and describe certain preferred embodiments of means for practicing my invention. However, my invention may be carried out by other means or mechanisms without departing from the spirit and scope thereof, as defined by the appended claims.

In the drawings:

Figure 1 is a view in perspective of a fragment of a conventional airplane wing or aerofoil showing a preferred form of aileron or flap for attaining the objects of my invention;

Figures 2 and 3 are fragmentary views of the left and right hand ends of an airplane wing when the lateral control has been actuated to raise the left hand side of the wing and restore the wing balance;

Figure 4 shows a modified form of aileron for practicing my invention; and

Figure 5 illustrates a type of structure in which the aileron carries a balancing surface spaced therefrom.

Referring now to the drawings in detail, in which like characters of reference are employed to designate similar parts in the several views, 1 indicates an airplane wing of a conventional curvature, the trailing edge of which adjacent to each end is cut-away to provide for the mounting of an aileron or flap 2, which is hingedly connected to the wing along the hinge line 3. The right and left hand ailerons are connected by suitable cables to an actuating element such as a "joy" stick or a wheel whereby they are simultaneously moved in opposite directions, to maintain or restore the equilibrium of the airplane on its longitudinal axis.

In normal flight, the position of the ailerons relative to the wing 1 is as shown in Figure 1. It will be observed that the aileron 2 is formed with a forwardly directed extension 4 which lies adjacent to the end of the wing. This extension 4, which is pref-

erably an integral part of the aileron structure, forms a balance for the aileron and is shaped to present a negative angle of incidence at normal flight, the angle of incidence at which the airplane is flying being the angle between the line of flight and the chord line of the plane; that is, a straight line drawn fore-and-aft tangent to the leading and trailing edges of the wing. Therefore, it will be evident that, when the ailerons at the opposite ends of the wing are in the position shown in Figure 1, the respective extensions 4 will neutralize each other and the normal flight of the plane will in no way be affected thereby.

Assuming now, that from one cause or another, the airplane banks or tends to rotate on its longitudinal axis in a direction toward the left, it is necessary, in order to restore the balance, to actuate the control to depress the left-hand aileron 2^a (shown in Figure 2), the right-hand aileron 2^b being simultaneously raised (see Figure 3). Manifestly, there is an increase in the resistance 25 of the aileron which is depressed, but at the same time the resistance of the extension 4^a of the left aileron 2^a (which rises as the aileron is depressed) is decreased, resulting in a considerable reduction in the total net increase in resistance at the left hand end 30 of the wing. On the other hand, the resistance of the right aileron 2^b, which is raised, increases but slightly, if any, owing to the well known properties of air flow around 35 wing sections, while the resistance of its component extension 4^b, which is directed downwardly, is greatly increased. It will be seen that the functioning of the balance surfaces 4^a and 4^b, as just described, creates 40 equal forces in opposite directions about a central vertical axis intersecting the horizontal axis of the airplane, the resultant of these forces having a torque equal to the torque produced by the warping of the ailerons. The differential in the resistance at 45 the opposite ends of the wing, which is an inherent disadvantage in the actuation of the ailerons in airplanes of the present types, being thus eliminated, there is consequently 50 no tendency of the airplane to deviate from its path of flight. It follows, therefore, that the use of the directional control, or rudder, in conjunction with the actuation of the lateral control to enable the aviator to maintain his path of flight, is unnecessary.

It is apparent that the relative dimensions of the various parts or surfaces by means of which my invention may be practiced may be readily determined by those skilled in 55 the art, so that when the ailerons are actuated, the resistance at the opposite ends of the wing will be equal and the described results attained.

In the modified structure, shown in Figure 65 4, it will be observed that the extension 4

of the aileron 2 is twisted or curved towards its forward edge so that part of it will present a negative angle of incidence, while in Figure 5 the balance element 6 is supported above the upper surface of the aileron 2 and 70 forward of the hinge line 3. This balance element 6, similar to the elements or extensions heretofore described, is set at a negative angle of incidence, the method of functioning of the structure shown in these latter 75 figures being the same as explained with reference to Figures 1 to 3 inclusive.

From the foregoing description, it will be noted that my invention is susceptible of incorporation in any type of airplane employing ailerons, or flaps, for effecting lateral control, the configuration and size of the ailerons and their component balance surfaces being suitable to the structure in which they are to be used.

What is claimed is:

1. The method of effecting lateral balancing of airplanes having a fixed wing or lifting surface and ailerons hinged to the opposite ends thereof which consists in counteracting the effect of the increased resistance to a depressed aileron at the same end of the wing, and simultaneously increasing the resistance at the other end of the wing to compensate for the decrease in resistance by the raising of the aileron at such end.

2. An airplane having a fixed lifting surface and ailerons hinged at opposite ends of the trailing edge thereof, each of said ailerons having a surface disposed at a negative angle of incidence at normal flight, said surfaces, when the ailerons are respectively raised and depressed, being adapted to compensate for the differential in pressure upon the opposite ailerons when actuated as afore- 105 said.

3. An airplane having fixed lifting surfaces, lateral controlling devices, directional control devices, and means for compensating for directional disturbance produced by the 110 manipulation of the lateral control devices, said means being independent of the directional control devices.

4. An airplane having fixed lifting surfaces, lateral controlling devices, directional 115 control devices, and means for compensating for directional disturbance produced by the manipulation of the lateral control devices, said means being independent of the directional control devices and operated by the 120 manipulation of the lateral control devices.

5. The method of stabilizing airplanes having fixed lifting surfaces which comprises the creation of unequal forces in opposite directions about a central vertical axis, 125 whose resultant has a torque equaling and opposed to the torque about said axis produced by the warping of the ailerons, said vertical axis intersecting the horizontal axis of the airplane.

6. An airplane having a fixed lifting surface and ailerons hinged at opposite ends of the trailing edge thereof, each of said ailerons having a surface disposed at a negative angle of incidence at normal flight, said surfaces, when the ailerons are respectively raised and depressed, functioning to create unequal forces at the opposite ends of the lifting surface, acting to counteract the torque produced about a central vertical axis of the airplane, by the actuation of the ailerons.
7. An airplane having a fixed lifting surface provided with lateral stabilizing devices at its opposite ends, each of said devices having a conjointly movable surface normally disposed at a negative angle of incidence, said surfaces, when the stabilizing devices are actuated, being adapted to create unequal forces in opposite directions about a central vertical axis of the airplane, whose resultant has a torque equalling and opposed to the torque produced by the raising of one stabilizing device and the depression of the other.
8. An aileron adapted for hinged connection to the trailing edge of an airplane wing, embodying an integral forwardly directed extension at its outer end, said extension being curved to present a negative angle of incidence at normal flight, and functioning to compensate for the differential in resistance set up by the actuation of the ailerons in the usual manner, which tends to rotate the airplane on its vertical axis.
9. An airplane having a fixed lifting surface or wing provided with stabilizing devices at its opposite ends, said stabilizing devices being capable of actuation to control the movement of the airplane about its longitudinal axis, each of said stabilizing devices being formed with an extension disposed at a negative angle of incidence at normal flight, said extensions being adapted to create unequal forces in opposite directions about a central vertical axis when the stabilizing devices are respectively raised and depressed, whose resultant has a torque equaling and opposed to the torque produced by the actuation of the stabilizing devices.
10. An airplane having a fixed lifting surface and ailerons hinged at opposite ends thereof adjacent to the trailing edge of said surface, each of said ailerons extending beyond the adjacent end of the lifting surface and having a forwardly directed portion disposed at a negative angle of incidence at normal flight, said aileron portions, when the ailerons are respectively raised and depressed, being adapted to compensate for the differential in pressure upon the opposite ailerons produced by the actuation thereof.
11. In an airplane having a fixed wing or lifting surface, the combination of an aileron movably mounted at each end of said wing or lifting surface and adjacent to the trailing edge thereof, each of said ailerons extending beyond the adjacent end of the wing or lifting surface and having a forwardly directed extension, the inner end of which is substantially parallel to the adjacent end of the wing or lifting surface, said extension having a downward inclination so as to present a negative angle of incidence in normal flight.

ANTHONY H. G. FOKKER.
